CONCRETE CONVEYER

Axel E. Lundbye, Nunda, N. Y., assignor to The Foote Company, Inc., Nunda, N. Y., a corporation of Delaware

Application May 25, 1935, Serial No. 23,490

4 Claims. (Cl. 198—119)

My invention relates to new and useful improvements in concrete pavers, and more particularly to the means of conveying the concrete from the mixing drum to its point of discharge at any desired position along the boom.

As is well known to those skilled in the paving art, the aggregates, with the exception of what is known as the "ready mix", are generally elevated by a skip to the drum of the paver, and after being thoroughly mixed are discharged into a bucket that travels outwardly on the boom and, in turn, discharged from the bucket at any predetermined point by the operator of the paver.

Also, as is well known, the boom and bucket method of discharge succeeded the previous method of discharging concrete from a paver by means of a relatively short chute that was traversed by the operator to discharge over a rather small radius.

At the present time, the tendency is to make the concrete pavers of greater capacity and the distribution of the concrete by the boom and bucket method presents certain difficulties as, for instance, a lengthy boom is necessarily heavy and when a large capacity bucket is filled with concrete and run out along the boom to its outer end there is a possibility of the paver becoming unstable.

Again, due to the extra capacity now of the drum, valuable time is lost in the delivery, that is, waiting after the bucket is emptied for the return of the bucket to a position under the discharge chute of the paver for another load.

One of the objects of the present invention, therefore, is to provide a concrete paver with an endless form of belt conveyer with the addition of what I term a discharge carriage and to so arrange the endless conveyer, the discharge carriage, and its other associated parts that the aggregates may be continuously discharged from the drum (after being properly mixed), carried on a conveyer belt to the discharge carriage, and from which carriage they will be delivered through a hopper to either or both sides of the boom. Provision is also made so that the discharge carriage may be positioned at any point along the boom for discharging the aggregates rather than only at the end of the boom.

Still another object of the invention is to provide a form of endless conveyer together with a movable discharge carriage that may be positioned at any point throughout the length of the boom, so that the discharge from the drum may be continuous, that is, after each batch

has been mixed, rather than filling up one bucket and closing the discharge chute until the bucket returns. The present invention, by providing an endless conveyer rather than one large bucket for the distribution of the concrete, will relieve the boom of any unstableness that would otherwise be caused by a heavy bucket of concrete at the end of the rather lengthy boom.

Still another object of the invention is to provide an endless form of conveyer together with a novel discharge carriage that has a bifurcated chute, so that the aggregates may be spread to either side of the boom and over a greater amount of sub-grade than is otherwise possible, thus doing away with the necessity of having several men shovel the concrete after the same has been discharged from the ordinary style bucket.

Still another object of the invention is to provide a form of endless carrier and distributing means wherein the discharge carriage may be quickly run out to a desired position by the operator and the endless conveyer discharge into and from this carriage in a rapid manner.

Still another object of the invention is to provide a form of endless conveyer belt, a discharging carriage, and a boom, which latter is universally mounted with respect to the paver, there also being a form of what might be termed transmission or power operating means driven from the engine of the paver which makes it possible and convenient to quickly traverse the boom and drive the conveyer belt, the carriage, and the other associated parts of the conveyer.

Still another object of the invention is to provide a form of endless conveyer belt and discharge carriage and to provide means for scraping or cleaning the belt as it travels, the scraping action taking place immediately after the materials have been discharged from the conveyer and again out at the end of the boom, so that the aggregates have no chance to harden or stick to the conveyer belt.

Still another object of the invention is to provide means for conveniently carrying out these several functions by the operator of the paver to thereby provide what might be termed "flexibility" to the machine.

With these and other objects in view, the invention consists in certain new and novel features and combination of parts, as will be hereinafter more fully explained and pointed out in the claims.

Referring now to the drawings showing a preferred embodiment,

Fig. 1 is a side elevation of my improved endless

conveyer provided with a cooperating movable delivery carriage;

Fig. 2 is a top plan view thereof;

Fig. 3 is an enlarged end elevation, partly in section to show the manner of distribution of the material from the discharge carriage to the oppositely arranged chutes;

Fig. 4 is an enlarged top plan of the rear end of the conveyer and showing the various operating mechanisms;

Fig. 5 is a side elevation of the same;

Fig. 6 is an enlarged transverse vertical sectional view on the line 6—6 of Fig. 5;

Fig. 7 is an enlarged fragmentary top plan view showing the adjustable discharge carriage and delivery chute and some of the associated parts;

Fig. 8 is a side elevation thereof and showing the means by which the belt is scraped during its travel;

Fig. 9 is an enlarged fragmentary plan view of the outer end of the conveyer and its associated parts;

Fig. 10 is a side elevation thereof and showing further means for scraping the belt during its travel;

Fig. 11 is a fragmentary detail showing the driving means for the scraper;

Fig. 12 is a fragmentary transverse vertical section of the conveyer and its supporting means taken on the line 12—12 of Fig. 9.

Referring now to the drawings, and more particularly to Figs. 1 and 2 for the moment, there is shown fragmentarily a paver 1, a portion of the bottom of the frame 2, the upright portion 3 of the frame, and a portion of the top frame 4. There may also be seen, fragmentarily, a portion of the mixing drum 5. The paver per se forms no part of the present invention but it is of the well-known Foote type as shown in several patents, to wit: 1,443,354, of January 30, 1923, granted to Charles E. Foote and 1,478,945, of December 25, 1923, granted to Charles E. Foote.

It will be noticed that there is a boom 6, but this type of boom is not conventional to the above Foote patents and does not carry a bucket of any of the well-known types that are generally associated with the booms of concrete pavers. The boom consists primarily of two channel beams 7, as may be seen from Fig. 3, while mounted on the boom is a carriage 9, which carriage will be explained more in detail as the specification proceeds.

It will be understood that there will be the necessary cross braces for the boom, and the inner end (the inner end being the end adjacent the paver) is supported on what I term a transmission mechanism which is located centrally of the paver 1 and directly beneath the spout 10, which spout extends into the drum of the paver and also into an auxiliary boot 11, which boot extends over the conveyer, as will be hereinafter described. The transmission mechanism, in turn, is mounted on the beams 8 forming part of a drop frame 12 permanently affixed to the front of the paver frame, the members 12 being suitably attached to the standards 3. This arrangement forms a drop seat or platform for the mounting of the casing 14 which, in turn, supports the pivotal end of the boom 6.

This present form of transmission mechanism makes it possible to elevate and to traverse the boom and to operate the conveyer from the power that operates the paver. The transmission per se forms the subject matter of a companion

application and will be described here in a general manner rather than specifically.

Referring again for the moment to Figs. 1, 4, 5, and 6, there will be noticed a main power shaft 13 which, in turn, is driven from the motive power (not shown) mounted on the paver. This power shaft 13 extends within the casing 14 of the transmission box and is provided at its end with a pinion 15, which, in turn, meshes with the bevel gear 16, which is mounted at the 10 end of the vertical shaft 17, which shaft extends through the bearing 18, and which bearing, in turn, has the integral upper plate 19 from which extends downwardly the flange 20. This flange 20, in turn, has secured thereto the gear 21 by 15 bolts 22, the gear, in turn, located above the plate 23 of the housing 14, which latter is bolted, as at 24, to the extension housing 25 of the housing 14 of the transmission box. The lower surface 26 of the main housing 25 of the transmission box or casing is secured by bolts 27 to the aforementioned channels 8.

Also located on the top plate 19 is a further housing 28, which forms the rotatable part of the transmission housing, through which passes 25 the transversely extending power shaft 29. This power shaft 29 is driven by the bevel gear 30 meshing with its mate 31 mounted on the upper end of the vertical shaft 17. The shaft 29 is suitably mounted in bearings 32 near the outer 30 end of the shaft and on each end there is provided a sprocket 33, each of which is provided with a chain 34 to, in turn, mesh with sprockets 35 that are mounted on the ends of the drum shaft 36, on which shaft there is the drum 37 35 that drives the conveyer belt 38.

As far as the specification has proceeded, therefore, it will be seen that the power derived from the rotation of the shaft 6 is directed through the various pinions and shafts and sprockets and 40 chains to operate the conveyer drum 37 and, in turn, the endless conveyer 38.

Also, by mounting the vertical drive shaft 17 in the housing 18 which, in turn, is rotatable in its casing, it will be seen that the boom is capable of traverse about the vertical axis coincident with the vertical shaft 17.

Mechanical means are provided for traversing the boom, and if reference is made to Figs. 4 and 5 there will be seen on the power shaft 13 a sprocket 39 provided with a sprocket chain 40 which, in turn, actuates the sprocket 41 mounted on the shaft 42. This shaft 42 is only fragmentarily shown and, of course, there will be the necessary bearings provided. On the end of the shaft 42 is the pinion 43 to operate the place clutch 44 which is made up of the two usual mitre gears 45 and 45' which are loosely mounted on the shaft 46. These mitre gears are provided with the interlocking face means (not shown) that may mesh with the shift collar 47 which is locked to the shaft 46, so that the shaft 46 and its worm 48 may be revolved in either direction, according to which mitre gear is locked to the shaft. Shifting means 48' are provided for selectively engaging either one of the mitre gears to be revolved by the pinion, depending on whether the boom is to be traversed to the right or to the left. The worm 48, of course, meshes with the aforementioned segmental gear 21, as will be understood from the several views. It will also be seen that the main power shaft 13 also furnishes the power for traversing the boom.

Now means for elevating the boom are also 75

shown, and although I have shown the means for manually elevating and lowering the boom it is within the province of the invention to mechanically operate the same.

Referring for the moment to Figs. 1 and 2, there is shown mounted on the main frame of the paver a transverse shaft 49 suitably mounted in bearings 50; while mounted near the opposite ends of the shaft 49 are the two worms 51 which, in turn, respectively mesh with worm gears 52 mounted on their respective drums 53. Separate cables extend from these drums to the forward end of the boom.

On the front of the machine and at the top thereof is pivotally mounted a bracket arm 54 with the outer bearings 55, through which passes a rod 56, and on the outer ends of this rod are the links 57. Held by the links 57, that is, on each side of the boom are the sheaves 58, and extending over these sheaves are the respective cables 59. As the cables are alike, a description of one will be a description of both.

The cable 59 extends forwardly from the drum 53 over one of the two sheaves 58 and thence to the end of the boom and over the sheave 60 held by the links 61, which links, in turn, are secured to the cross rod 62 at the outer end of the boom. The cable is then returned and passes over the other of the sheaves 58 and thence forwardly again and fastened to a fixed arm 61' formed on the link 61. This arrangement is duplicated on the opposite side of the boom so that when the hand wheel 63 is operated the two drums 53 will be wound or unwound in unison, depending, of course, upon the direction of rotation of the handle, and the boom will thereby be elevated or lowered, as will be readily understood.

Now referring more particularly to the endless conveyer 38 and its discharge carriage and other associated parts, there will be noticed the usual supporting rollers 64 spaced along the boom and supported by the usual brackets for supporting the conveyer belt and also the under roller 64'. The belt may be of fabric, rubber, or other desired material. There is also provided at the outer end of the boom a drum or roller 65 which is mounted on the shaft 66, which shaft, in turn, is mounted in bearing blocks 67 on the boom. These bearing blocks are adjustable so that the proper tension may be placed on the conveyer belt at all times.

By glancing at Figs. 1 and 2, however, it will be noticed that the conveyer 38 does not run directly from the inner drum 37 to the outer drum 65 but, in turn, passes upwardly and is threaded about a discharge carriage 9 and then outwardly to the end of the boom and over the outer roller and then back to the inner drum. This discharge carriage 9 may be seen in detail in Figs. 7 and 8, and its provision makes it possible to discharge the aggregates at any desired place along the boom rather than conveying the material to the end of the boom, which is the practice of ordinary endless conveyers.

The discharge carriage consists of the side frames 69 which are mounted on the wheels 70 which, in turn, operate on the tracks 71 (see Fig. 8). These side frames 69 are of odd shape, that is, they rise from a point 72 at what might be termed their rear end and extend upwardly to the point 73 at one angle and then sharply upwardly, as at 74, to their outer ends 75. The forward ends of the side frames are cut out, as at 76, to, in reality, form the legs 77 and also a leg 78, which latter extends forwardly out over the forward wheels. Mounted on the upper surface of

the carriage 9 is shown a roller 79 similar to the rollers that extend along the entire boom for the support of the belt conveyer.

Now before explaining how the conveyer is threaded through the carriage, reference will be made to what I term the carriage discharge hopper 80, which forms a part of the discharge carriage, and this hopper may be seen also in detail in Fig. 3. This hopper is secured to the forward arms of the carriage and consists of what might be termed the body portion 81. Its lower end is bifurcated to form the two separate branches 82 and 83 (Fig. 3), which extend laterally of the boom and outwardly to a position about in line with the caterpillar tractors 84 of the paver.

It will be noticed that the hopper 80 is open at its rear, that is, in the upper portion 81, as at 85, and extending transversely of the hopper is the shaft 86. Mounted on this shaft is the drum or roller 87 over which the endless conveyer is passed. To a point at the rear of the hopper and on the carriage, mounted in the side frames of the same, is another shaft 88, on which is mounted a drum or roller 89, so that the endless conveyer belt, after passing over the drum in the top of the hopper, will again extend rearwardly around the roller 87 of the carriage and then extend outwardly and over the idlers until it reaches the drum 65 mounted at the forward end of the boom. Of course, from this point the conveyer belt extends rearwardly to the drum 37 mounted at the inner end of the boom over the idlers 64'.

It might be mentioned here that regardless of where the carriage is positioned along the boom, the length of the conveyer belt will always remain constant, so that it is not necessary to use longer or shorter belts, which might otherwise be the case.

Referring for the moment to Fig. 3, it will be noticed that I have provided means to direct the aggregates from the hopper either into the branch 82 or into the branch 83 by the provision of a gate 90 operating from the shaft 91, which may be provided on its outer end with a handle 92. The swinging of this gate in one direction will, of course, direct the aggregates to the branch in the opposite direction, so that the concrete may be equally well disposed to either side of the boom. Or, if desired, the gate could be placed in a vertical position to direct the aggregates to both sides at the same time.

When an endless form of conveyer is used for the disposition of concrete, unless some provision is made for cleaning the belt the aggregates are likely to harden on the belt and continue to build up until they affect the normal operation of the belt. I have, therefore, provided two separate means for cleaning or scraping the upper surface of the belt throughout the entire operation of the same. By referring for the moment to Figs. 1 and 3, there will be seen located directly beneath the shaft 86 in the hopper a second shaft 93, which is suitably mounted in bearings 94, while at the one end 95 there may be seen a sprocket 96 and a chain 97, which latter extends to a sprocket 98 mounted on the end 99 of the shaft 86.

Now mounted on this shaft 93 and directly beneath the drum 87 and in contact therewith may be seen a scraper 100 which may be provided with helically-shaped blades 101, which contact with the outer surface of the belt and on which surface, of course, the concrete has been carried. It will be understood that the endless con-

veyer rotates the drum 87 by its movement thereon and power, of course, is derived from the shaft supporting this drum to the scraper through the chain and sprockets just mentioned.

In the same manner, a further scraper 102 is provided at the outer end of the boom and the driving arrangement may be seen in detail in Fig. 11. In this instance, there is a sprocket 103 mounted on the one end of the shaft 66, over which passes the chain 104 to operate the sprocket 105 mounted on a shaft 106, which shaft is supported in the bearings 107 mounted on the under sides of the channel beams 7, and on which shaft is the helically-bladed scraper 102. This drum 65 is what might be termed an idler drum, but it is driven by the movement of the conveyer belt which, in turn, through the chain and sprockets just-mentioned operates this scraper 102. The scraper is mounted directly beneath the aforementioned drum 65, so that any of the aggregates that were not removed by the scraper 100 will be removed by the scraper 102 mounted at the outer end of the boom. Thus, the belt is always kept clean and the aggregates are prevented from hardening on the belt during times when the belt is not in operation.

Having described the boom and the belt conveyer together with the discharge carriage and its hopper, the mechanical means for positioning the carriage and its hopper at any desired point along the boom will now be described.

In Fig. 7, it will be noticed that the carriage 9 is provided with two rear arms 108 and 109 which are oppositely disposed and extend rearwardly 35 and outwardly over the channels of the boom.

Taking up the lower one, Fig. 7, it will be seen that a cable 110 is attached to the eyelet of the arm 108 and then extends rearwardly (Fig. 4) to a drum 111, which is mounted at the one end 40 of the laterally extending shaft 113, which shaft is suitably mounted in the bearings 114. This cable 110 is then threaded about the drum 111 and has the other bight extending forwardly (see Figs. 2 and 9) to a loose pulley 115 mounted on the shaft 66 at the forward end of the boom. The cable extends rearwardly again to an arm 116 (Fig. 7) which is secured to the forward end 45 of the carriage 68, which arm is similar to the aforementioned arm 108, the cable being fastened through an eyelet 117 on said arm.

In the same manner, there is another arm 118 at the forward end of the carriage and on the same side of the carriage as the arm 109, and there is also a cable 119 secured to the arm 109, which cable extends rearwardly over the drum 120 mounted on the opposite end of the shaft 113. After being threaded around this drum, the cable extends forwardly of the boom and around a loose pulley 121 located on the shaft 66 and then extends rearwardly and is secured to the aforementioned arm 118.

Thus, it will be seen that there are cables extending toward the rear of the machine, around drums, and forwardly around pulleys and back to the carriage, so that a movement of these drums 111 and 120 will cause the carriage to move forwardly or rearwardly, depending on which way the drums are rotated.

Now to rotate these drums in the desired direction, I provide a face clutch 122 which consists of the usual oppositely located mitre gears 123 and 124 with the slip collar 125 disposed therebetween which is rotatively locked to the shaft 113, and this collar is operated through the

arm 126 and rod 127, so that the collar may be locked in the well-known manner to the face of either one of the mitre gears. These mitre gears are turned in the opposite direction by the pinion 128 located on the stub shaft 129 which, in turn, is provided at its other end with a pinion 130 that is rotated by the bevel gear 131 which is mounted on the shaft 36 on which, it will be remembered, is mounted the main driving pulley or drum 37. Therefore, as will be readily understood, whenever the shaft 36 is turning, power may be selectively applied to either one of the mitre gears of the clutch to revolve the drums 111 and 119 in either one of the two directions to thus drive the carriage out along the boom 15 or to pull back the carriage to any desired location on the boom.

It will also be noticed that all of the operations of the endless conveyer, the discharge carriage, and the traversing of the boom are mechanically operated indirectly from the main drive shaft 13, the only manual operation being the elevation or lowering of the boom.

Before describing the complete operation of the conveyer and its carriage, it might be mentioned that in Fig. 5 there is shown in the supplemental chute 10' a manually operated gate 132 provided with a handle 133, which gate is arcuate in shape and provides means for cutting off or regulating the rate of discharge of the aggregates to the boot and, of course, to the endless conveyer.

Operation

The operation of the boom and its conveyer is 35 exceedingly simple, and presuming that the paver is positioned along a sub-grade, if it is desired to move the boom 6 to the right or left it will only be necessary to operate the clutch 44 by moving the lever in the desired direction and 40 power, of course, will be provided from the power shaft 13 to the shaft 42 to, in turn, rotate the worm 48 which, meshing with the segmental gear 24, will traverse the boom in the desired direction.

Inasmuch as the shaft 13 is rotating, it will, through the pinion 15, gear 16, shaft 17, and pinions 31 and 30, drive the main drive shaft 29 and through the sprocket 33 and chains 34 drive the rear pulley or drum 37. This, in turn, will 50 operate the endless conveyer belt 38.

Now supposing that it is desired to run the discharge carriage 9 out to a point near the end of the boom 6, the operator will move the rod 127 to selectively turn the drums through the 55 clutch 122 to thus rotate the drums 111 and 120 in the desired direction. The cables 110 and 119 threaded about these drums will then take up and pay off and advance or retract the carriage to the desired position, it being remembered that the clutch 122, in turn, receives its power from the pinion 128 driven from the pinion 131 on the shaft 36.

After the carriage is in the desired location, and presuming the aggregates are to be dumped 65 to the right of the machine the small gate 90 will be revolved to the position shown in Fig. 3. Inasmuch as the power shaft 13 is revolving, the shaft 29 will be revolving, as will be remembered, and also the shaft 36, and the endless conveyer 70 belt will be traveling outwardly and over the rollers or drums mounted on the carriage 9. Also, the two scrapers, due to their driving means connected with the drum on the discharge carriage and the drum on the end of the boom, will be 75

driven by their chains and sprockets, so that after the batch has been thoroughly mixed in the mixing drum, the drum discharge chute 10 will be opened and the aggregates fed through the discharge and supplemental chute 10', and the gate 132, being regulated by the handle 133, will permit the desired amount of aggregates (not shown) to fall on the endless conveyer belt 38.

10 The material will travel outwardly on the belt and then upwardly along the discharge carriage, and as the conveyer belt passes over the drum 37 the aggregates will fall into the hopper 80 and some will pass directly out of the branch 82 while others, striking the gate 90, will also be deflected into the branch 82, and as the conveyer belt continues in its motion the concrete will be continuously fed from the chute 82 as fast as it is fed onto the conveyer.

20 As any given point of the belt passes over the drum 37, any sticking aggregates will be removed by the revolving scraper 100. The belt then travels inwardly into the carriage and around its pulley and then outwardly to the end 25 of the boom over the drum 65, and as it passes under the drum it will be brushed by the sprocket driven scraper 102. The belt (given point) then returns to the drum 37 at the rear of the boom and then starts out on another cycle.

30 Of course, the gate 90 can be swung in either direction to dispose of the aggregates on either side of the machine, or the gate might be left in a vertical position to distribute some aggregates on the one side and some on the other.

35 It will be understood that it is but the matter of a moment to move the discharge carriage along the boom, and this movement can take place either while the concrete is on the conveyer belt or before the conveyer belt is loaded with the 40 concrete.

From the foregoing, it will be seen that I have provided means for distributing the aggregates in a continuous manner at any point intermediate the ends of the boom.

45 Inasmuch as the present tendency is to make mixing drums of relatively large capacity and as the size of the ordinary bucket used on the booms has to be of a limited nature, time has been lost while waiting for the return of the bucket.

50 Furthermore, when the aggregates are disposed in the present manner, they have a tendency to spread further over the sub-grade than where say a cubic yard of concrete is dropped from the bucket at the one time.

55 Also, by providing mechanically operated scrapers, one located at the discharge carrier hopper and the other out at the end of the boom, there is no possibility of the aggregates drying on and sticking to the endless conveyer belt.

60 Finally, it will be seen that all the power necessary to drive the endless conveyer and to move the carriage forwardly or rearwardly on the boom is derived from a central point, that is, the transmission over which the inner end of the 65 boom is located.

I am aware that it is old to provide conveyers in combination with concrete pavers and do not claim my invention broadly as such, but what I do claim and desire to secure by Letters

70 Patent is:—

1. In combination with a concrete paver, a supporting means and power transmission located centrally and in front of the paver, and a boom centrally mounted at its one end on said support-

ing and transmission means, means cooperating with the transmission means and with the boom for selectively traversing the boom in the desired direction, an endless conveyer belt mounted on the boom, means cooperable with the transmission mechanism for driving said conveyer, a discharge carriage provided with a hopper mounted on the boom, selective means cooperable with the transmission mechanism for directing a forward or rearward movement of said discharge carriage 10 on said boom, the discharge carriage provided with two rollers, and the conveyer belt passing over one and under the other and then to the forward end of said boom whereby material on said conveyer belt will be discharged to said 15 hopper.

2. In combination with a concrete paver, a supporting means and power transmission located centrally and in front of the paver, a boom centrally mounted at its one end on said 20 supporting and transmission means, means cooperating with the transmission means and with the boom for selectively traversing the boom in the desired direction, an endless conveyer belt mounted on the boom, means cooperable with the transmission mechanism for driving said conveyer, a discharge carriage provided with a hopper mounted on the boom, selective means for 25 directing a forward or rearward movement of said discharge carriage on said boom, cooperable with said transmission mechanism, the discharge carriage provided with two conveyer rollers, the conveyer belt passing over one and under the other and then to the forward end of said boom whereby material on said conveyer belt will be 30 discharged into said hopper.

3. In combination with a concrete paver, a power transmission located centrally in front of the paver, a boom centrally mounted at its one end on said transmission, means cooperating with the transmission and with the boom for selectively traversing the boom in any desired direction, an endless conveyer belt mounted on the boom, means also cooperable with the transmission mechanism for driving said conveyer, a discharge 45 carriage provided with a bifurcated hopper mounted on the boom, the endless conveyer passing over and through said carriage, selective means also operable with said transmission for directing a forward or rearward movement of the 50 discharge carriage on said boom, and means for directing the aggregates to either side of the bifurcated hopper after leaving the conveyer.

4. In combination with a concrete paver, a combined supporting means for the boom and power transmission located centrally in front of the paver, a boom centrally mounted at its one end on said supporting means and power transmission, means cooperating with the transmission and with the boom for selectively traversing the boom in the desired direction, an endless conveyer belt mounted on the boom, means also cooperable with the transmission mechanism for driving said conveyer, a discharge carriage mounted on said boom and provided with a bifurcated hopper the legs of which extend downwardly from the opposite sides of the boom, the endless conveyer cooperating with the carriage to discharge the contents of the conveyer, selective means also cooperable with the transmission 70 means for directing a forward or rearward movement of said discharge carriage on said boom.

AXEL E. LUNDBYE.
